George J. S. Collins,
By Edwin Guthrie,

Attorney

UNITED STATES PATENT OFFICE.

GEORGE J. S. COLLINS, OF ST. LOUIS, MISSOURI.

VALVE-SEATING TOOL.

Application filed August 25, 1921. Serial No. 495,238.

To all whom it may concern:

Be it known that I, GEORGE J. S. COLLINS, citizen of the United States, residing at St. Louis, in the county of St. Louis and 5 State of Missouri, have invented certain new and useful Improvements in Valve-Seating Tools, of which the following is a specification.

This invention relates to valve seating 10 tools, and belongs to that class of implements or appliances intended to be used to face the valve seats of a gasoline motor, either before the motor is placed in the vehicle originally, or after it has been regularly installed. The valve seats are seldom 15 perfectly true in a new motor, and implements of the character of this invention are designed to cut the seats accurately, in order that the angle of the valve head and the corresponding angle of the valve seat may fit 20 perfectly when placed together.

The object of this invention is the production of a hand tool device comprising parts of special construction and arrangement whereby it is believed the valve seats 25 may be accurately cut, and whereby an especially strong, easily operated and effective instrument is made, the proper use of which does not depend upon the skill and 30 ability of the mechanic to hold the tool in exact alignment, but is held and revolves accurately by reason of the particular structure disclosed herein.

To illustrate the special construction and 35 arrangement of the various parts of this invention, the accompanying drawings are made a part of this application. Fig. 1 represents a vertical sectional view of the upper portion of a motor casing or cylinder 40 block, showing this invention, also drawn in vertical section, applied to the valve seat of the casing. Fig. 2 is a cross-section of the lower portion of the revolvable body or cutter holder, and the stationary rod, the 45 section being taken on the broken line 2-2 of Fig. 1. Fig. 3 is a top view of the dial nut and stationary rod, showing the dial on the nut and indicating mark on the head of the rod. Fig. 4 is a top plan view of the body 50 or holder, the dial nut being removed to exhibit the washer lying beneath it and the engagement of the washer and the upper longitudinal slot in the rod.

Throughout the drawings and description, 55 the same letter is employed to refer to the same part.

Considering the drawings, the cylinder block or casting A of a motor has the customary valve seat a, the wall or surface of which is inclined following the usual practice in such contrivances. To rectify any imperfection in the angularly disposed surface constituting the valve seat, the cutter B is provided, which has a central tapering 60 passage b ground to tightly fit the tapering end c of the body or tool holder C. The body C is ordinarily T-shaped and the extended sides are given suitable threaded sockets for handles E and e by which the revolvable body is turned upon the central 65 and stationary rod F. The body C and cutter are fed lengthwise of the rod by a thumbnut G engaging the upper threaded end f, of the rod, and the nut will be again mentioned. 70

The rod F on its lower end carries the cylindrical member H, having the sharpened edge h arranged to bite the end of a valve stem guide forming a part of the casting A as illustrated in Fig. 1, and a nut J, engaging the threaded end j of the rod F, acts as a keeper and prevents the member H from being forced off the rod F in operation. As shown in Fig. 1 the lower end of the rod F has a longitudinal slot K, and a pin k passes through the wall of the biting member H and engages the slot K. Thus, it will be understood when the member H is forced to bite the end of the valve stem 80 guide, the rod F is held stationary. 85

Considering Figs. 1, 3 and 4, it will be observed that the upper end of the rod F has also a slot L running lengthwise of the rod, and a washer M, lying upon the upper finished surface g of the body or holder C, 90 has a lug m engaging the slot L. The purpose of the introduction of the washer and its engagement with the rod F, is to prevent the turning of the rod by the rotary movement given the thumbnut G when feeding 95 the cutter, and to prevent the loosening of the thumbnut after adjustment when the body C is revolved to operate the cutter. 100

As illustrated in Fig. 3, the upper surface of the thumbnut G has a dial N inscribed thereon, and the head of the rod F is provided with an indicating mark or pointer n. 105

In Fig. 1, the extended sides of the holder or body C are designated by the reference letter D, and the threaded sockets for 110 the correspondingly threaded ends of the handles E and e are marked d.

2

In the operation of this invention, the rod F is passed through the valve stem guide of the cylinder block A, and the biting member H is slipped on the lower end of the rod and held there by the nut J. The holder or body C being placed on the rod with the cutter B in the valve seat a, the thumbnut G is applied; and as the cutter is forced against the valve seat the rod F is equally drawn upon and the edge h of the member H caused to bite the end of the valve stem guide holding the rod F stationary. To feed the cutter the thumbnut G is turned, and the amount of feed is indicated upon the dial N. The lower portion of the rod F fits the valve stem guide accurately, and it also fits accurately the passage or bore extending lengthwise through the body C, thus centering the cutter perfectly and keeping it in position. As illustrated the body C is bored out axially and made an exact although movable fit for the rod F, and the body is revolved around the rod as an axis, the rod being stationary, thus insuring a very accurate cutting of the valve seat, the amount of which is measured by inspecting the dial with respect to the indicating mark upon the rod. The cutter is intended to be made of the best tool steel available for the purpose, and it is connected with the lower end of the body C by a tapering joint in order that it may be slipped off and replaced when occasion arises. When the cutter is forced by the thumbnut G into cutting relation with the valve seat, the cutter turns evenly and freely with the body and acts without "chattering" or other vibrations, and by reason of the special construction herein described, this invention may be successfully used even by inexperienced persons.

Having now described this invention and explained the mode of its operation, what I claim is:—

1. In a valve seating tool, the combination with a rod, of a body revoluble and adjustable upon the rod and provided with a cutter, and a member secured to the lower end of the rod against rotary movement on the rod, the said member having a sharpened portion for biting into the end of a valve stem guide or the like to hold the said rod against rotation.

2. In a valve seating tool, the combination with a stationary rod having a threaded lower end and a longitudinal slot in its

lower end, of a removable member movable lengthwise on the rod and having a projection engaging the said slot, the upper part of the said member having a sharp edge for biting the end of a valve stem guide or the like to hold the said rod stationary, a nut engaging the lower and threaded end of the rod to keep the said member upon the rod, a revoluble body provided with a cutter and movable lengthwise on the rod, and means for forcibly moving the body along the rod to feed the cutter.

3. In a valve seating tool, the combination with a stationary rod, of a member mounted upon the lower end of the rod and having a sharpened edge for biting the end of a valve stem guide or the like to hold the rod stationary, means for keeping the member upon the rod, a revoluble body movable lengthwise on the rod and provided with a cutter, and means for forcibly moving the body on the rod to feed the cutter.

4. In a valve seating tool, the combination with a stationary rod, of a member mounted upon the lower end of the rod and having a sharpened projecting portion for biting the end of the valve stem guide or the like to hold the rod stationary, a revoluble body movable lengthwise of the rod and provided with a cutter, the upper end of the said rod being threaded, a thumb nut engaging the said threaded end of the rod for forcibly moving the body lengthwise of the rod to feed the cutter, an indicating mark on the rod, and a dial carried by the thumb nut and arranged in conjunction with the said indicating mark to measure the movement of the body and feed of the cutter.

5. In a valve seating tool, the combination with a stationary rod, of means borne by the lower end of the rod and having a sharpened projecting portion for biting the end of a valve stem guide or the like to hold the rod stationary, a revoluble body provided with a cutter and movable lengthwise on the rod, means for forcibly moving the body along the rod to feed the cutter, and indicating devices carried by the said rod and the said body-moving means for indicating the movement of the said body and feed of the cutter.

In testimony whereof I affix my signature.

GEORGE J. S. COLLINS.
